THROAT PLATE FOR OVEREDGE SEWING
MACHINEJohn M. Washburn, West Hartford, Conn., assignor to
The Merrow Machine Company, Hartford, Conn., a
corporation of ConnecticutFiled Aug. 19, 1960, Ser. No. 59,643
2 Claims. (Cl. 112—260)

This invention relates to overedge sewing machines, and more particularly to throat plates for use in overedge sewing machines wherein multiple needles are employed to form fabric penetrating loops passing through the fabric at different distances from the fabric edge.

The invention has particular utility in the formation of overedge seams where two plies of fabric are joined by the seam in edge to edge abutment. In the formation of overedge seams, two plies of fabric to be joined are fed through the sewing machine with one ply of fabric overlying the other and with the edges of the plies along which the seam is to extend in vertical alignment with each other. The machine passes a loop of thread downwardly through both plies of fabric. Elements of the machine manipulate the loop to draw the loop outwardly beneath the lowermost ply to the fabric edge. This loop may be then drawn upwardly around the edges of both plies and brought to a point overlying the uppermost ply of fabric at which the loop is then pierced by a subsequent fabric penetrating loop or, in other types of seams, a covering thread loop may be passed through the fabric penetrating loop, brought upwardly around the edge and over the upper surface of upper ply to be pierced by a subsequent fabric penetrating loop. In either case, the seam, as completed by the machine, finds the two plies of fabric in overlying relationship with the seam extending along a common edge of the two plies. In many cases, after the fabric has been seamed, it is desirable to open out the two plies about the seam so that when the two plies are placed on a flat surface, the seamed edges of the two plies are in edge to edge abutment, rather than the overlapping relationship in which the seam was formed by the machine.

It is frequently desirable to form an overedge seam by forming two series of fabric penetrating loops by employing a pair of needles in side by side relationship, the fabric penetrating loops formed by one needle penetrating the fabric at points lying along a first line extending parallel to the edge of the fabric and the loops formed by the second needle penetrating the fabric at points lying along a second line spaced at a greater distance from the fabric edge than the line of penetration points of the first needle. The fabric enclosing capacity of the loops formed by the respective needles is determined during the stitch forming operation and hence, when the fabric plies are subsequently opened out to form an abutted edge seam, those loops which penetrate the fabric at points most distant from the fabric edge must be longer than the loops penetrating the fabric at points more closely adjacent the fabric edge. In the complete abutted seam, if the loops which penetrate the fabric at points most distant from the fabric edge are not sufficiently and uniformly longer than the loops which penetrate the fabric nearest the fabric edge, a greater tension will be placed on the loops of one needle thread than on the loops of the other needle thread.

It is a primary object of the invention to provide an overedge sewing machine employing two or more needles to form two or more series of fabric penetrating loops wherein the fabric enclosing capacity of the various loops may be determined during the stitch forming operation to achieve substantially equal tension in all needle threads

2

when the work material is subsequently opened out to form an edge abutted seam.

Other objects and features of the invention will become apparent by reference to the following specification and to the drawings.

In the drawings:

FIG. 1 is a perspective view of one type of seam which may be formed with the use of a throat plate embodying the present invention showing the seam as it is formed

10 by the machine;

FIG. 2 shows the seam of FIG. 1 opened out into its completed form;

FIG. 3 is a front view, partially in section, with certain parts broken away or omitted, of a "Merrow" overedge
15 machine;

FIG. 4 is a plan view of a throat plate embodying the invention;

FIG. 5 is a side elevational view of the throat plate
of FIG. 4;

20 FIG. 6 is a cross-sectional view taken on line 6—6
of FIG. 4;

FIG. 7 is a partial cross-sectional view taken on line
7—7 of FIG. 4; and

FIG. 8 is a cross-sectional view taken on line 8—8
25 of FIG. 4 showing the thread-fabric relationship during
the seam formation.

It is believed the invention will be best understood by a brief description of the manner in which an overedge seam of the type with which the invention is concerned
30 is formed. FIG. 3 is a cross-sectional view, with certain parts omitted, of a well known "Merrow" overedge sewing machine. The machine includes upper and lower shafts 10 and 12 journaled in the machine frame 14 for rotation and synchronously rotated by conventional
35 means, not shown. A pair of thread carrying needles 16 and 18 are mounted in side-by-side relationship upon a needle carrier 20 which is driven in rotary oscillation about the axis of a pivotal support designated generally
40 22. Needle carrier 20 is oscillated in a conventional manner by an eccentric pin 24 at the outer end of upper shaft 10. In FIG. 3, the needles are shown at approximately the mid point of their rotary oscillation, the lower limit of movement of needles 16 and 18 locating the needles below the path of movement of lower looper 26
45 while the upper limit of movement locating the tips of needles 16 and 18 somewhat above looper 28. For further details of the needle carrier and its movement relative to various parts of the machine, see United States Patent No. 2,755,757, granted on July 24, 1956 to Bernard
50 N. Pierce.

Each of shafts 10 and 12 carries a cylindrical cam such as 30 and 32. Cam groove 34 in upper cam 30 and cam groove 36 in lower cam 32 control the movement of upper looper 28 in a manner well known in the art
55 while a second cam groove 38 in lower cam 32 controls the movement of lower looper 26. Movement of needle carrier 20, lower looper 26 and upper looper 28 is thus coordinated in a manner well known in the art to produce a seam such as that shown in FIG. 2 in the following manner.

Work material to be seamed is placed upon the upper surface of a throat plate 40 with the plies (M1 and M2) to be joined in overlapping relationship as in FIG. 1, the edge along which the seam is to be formed extending along edge 42 of throat plate 40. Feeding mechanism (not shown) in the machine feeds the material in movement synchronized with needles 16 and 18 in a direction directly away from the observer in FIG. 3. Needles 16 and 18 each carry a separate needle thread, thread 44 of FIG.
60 1 being carried on needle 16 while thread 46 is carried on needle 18. A third, or covering thread 48 of FIG. 1

is carried by and passes through the eye 50 of lower looper 26.

Downward movement of needles 16 and 18 from the position of FIG. 3 carries the needles and their respective threads through both plies of work materials supported upon throat plate 40 at penetration points 52 and 54. Needles 16 and 18 pass downwardly through aligned openings in throat plate 40 to a point where the thread loops carried by the respective needles are located in the path of movement of lower looper 26. At this time, the 10 lower looper moves to the right from its position in FIG. 3 and the point of the lower looper passes between the respective threads 44 and 46 and their needles 16 and 18. A loop of each of threads 44 and 46 is thus retained on the lower looper to the left and below eye 50. This 15 movement of the lower looper also projects a loop of thread 48 through the respective retained loops in threads 44 and 46.

The loop of thread 48 is carried to the right by eye 50 of lower looper 26 outwardly beyond edge 42 of throat plate 40 at the time upper looper 28 moves to a position below and to the left of eye 50 of lower looper 26, and the point 29 of the upper looper 28 passes upwardly between the back side of lower looper 26 and the thread 48, thus placing a loop of thread 48 in the throat 29' of upper looper 28. The upper looper 28 carries this loop of thread 48 upward and over the plies of material supported by the throat plate 40 to a point where the next downward movement of needles 16 and 18, carrying threads 44 and 46 respectively, pass through the loop of covering thread 48. Tension on thread 48 retains the respective loops of threads 44 and 46 in the manner best shown in FIG. 1 as the lower looper returns to position shown in FIG. 3. The feeding mechanism of the machine (not shown) feeds the material one step away from the observer in FIG. 3 so that the loop of covering thread 48 is passed through by the loops of needle threads 44 and 46 in the next subsequent stitch.

To permit the seam as shown in FIG. 1 to be opened out into the relationship of FIG. 2, the seam as completed by the machine finds a certain amount of slack in the loops of threads 44 and 46. This amount of slack is determined by the thickness of throat plate 40 since, as formed by the machine, each of the loops in threads 44 and 46 pass beneath and around stitch fingers 56 and 58 on the throat plate. As indicated in FIG. 1, those portions of the loops of thread 44 which project to the right of the fabric edge in FIG. 1—i.e. the slack referred to above—are substantially equal in length and fabric enclosing capacity to the corresponding portions of the loops of thread 46. However, as is apparent from FIG. 2, opening out of the fabric plies into the FIG. 2 relationship takes up a much greater amount of slack from the loops of thread 44 than from the loops of thread 46. Thus, the tension applied to thread 44 in the completed seam of FIG. 2 differs from the tension applied to thread 46. To obtain equal tension in both threads, the conventional throat plate shown in section in FIG. 3 is replaced with a throat plate 60 embodying the invention and shown in FIGS. 4 through 8 of the drawings.

In FIGS. 4 through 8, a throat plate 60, designed to replace throat plate 40 of FIG. 3, is disclosed as being formed with an elongate opening 62 within which feed dogs may be located to feed work material across the throat plate and a bore 64 employing a means for mounting throat plate 60 upon the frame of the machine. Reference is made to United States Patent No. 2,233,088, granted February 25, 1941, to John M. Washburn which discloses, particularly in FIG. 3 of the patent, the relationship between the throat plate and other component parts of the machine. The path of movement of needles 16 and 18 is indicated in cross-hatched areas 16' and 18' respectively in FIG. 4. As best seen in FIG. 4, the needles pass downwardly adjacent a side edge 66 of throat plate 75

60 and rearwardly (with respect to the direction of feed of material indicated by arrow F) of a projection 68 which projects laterally outwardly from side edge 66.

Two stitch fingers 70 and 72 extend from projection 68 in parallel spaced relationship to side edge 66. As seen in FIG. 4, needle 16 passes through the throat plate between stitch finger 70 and side edge 66 at a location adjacent the base of stitch finger 70, while needle 18 passes between stitch fingers 70 and 72 adjacent their bases. As best seen in FIGS. 5 through 7, the upper side surfaces of stitch fingers 70 and 72 lie in a generally horizontal plane coplanar with the general top surface of throat plate 60. The lower side surfaces 74 and 76 of the respective stitch fingers 70 and 72 are inclined upwardly in a direction away from their respective bases so that loops of threads 44 and 46 formed around the respective stitch fingers are easily pulled from the stitch fingers as the work material is fed through the machine. As shown most clearly in FIGS. 5 and 8, stitch finger 70 is substantially thicker in its vertical extent than is stitch finger 72 and, as is apparent from FIG. 8, the variation in thickness thus enables a substantially greater amount of slack to be placed in the loops of thread 44 (carried by needle 16) than is placed in the loops of thread 46 (carried by needle 18) during the formation of the loops by operation of the needles and loopers in the manner described above.

While one embodiment of the invention has been disclosed, it will be apparent to those skilled in the art that the disclosed embodiment may be modified. Therefore, the foregoing description is to be considered exemplary rather than limiting, and the true scope of the invention is that defined in the following claims.

I claim:

- 35 1. In an overedge sewing machine having a pair of needles in side-by-side relationship; a throat plate having a side edge and a projection extending laterally from said side edge, a first elongate stitch finger secured at its base to said projection and extending horizontally from said projection in spaced parallel relationship with said side edge to define a first needle receiving opening between said first finger and said side edge, a second elongate stitch finger secured at its base to said projection and extending horizontally from said projection in parallel relationship to said first stitch finger to define a second needle receiving opening between said first and said second fingers, the vertical thickness of said first finger at any longitudinal position thereon being greater than vertical thickness of said second finger at the corresponding longitudinal position.
- 40 2. In an overedge sewing machine having a pair of needles in side-by-side relationship; a throat plate having a side edge thereon and a projection extending laterally from said side edge; a first stitch finger secured at its base to said projection and extending horizontally from said projection in spaced parallel relationship to said side edge, to define a first needle receiving opening between said first finger and said side edge, a second stitch finger secured at its base to said projection and extending horizontally from said projection in spaced parallel relationship to said first finger to define a second needle receiving opening between said first and said second finger, said second finger having a vertical thickness at any longitudinal position thereon being greater than vertical thickness of said first finger at the corresponding longitudinal position.
- 45 3. In an overedge sewing machine having a pair of needles in side-by-side relationship; a throat plate having a side edge thereon and a projection extending laterally from said side edge; a first stitch finger secured at its base to said projection and extending horizontally from said projection in spaced parallel relationship to said side edge, to define a first needle receiving opening between said first finger and said side edge, a second stitch finger secured at its base to said projection and extending horizontally from said projection in spaced parallel relationship to said first finger to define a second needle receiving opening between said first and said second finger, said second finger having a vertical thickness at any longitudinal position thereon being greater than vertical thickness of said first finger at the corresponding longitudinal position.
- 50 4. In an overedge sewing machine having a pair of needles in side-by-side relationship; a throat plate having a side edge thereon and a projection extending laterally from said side edge; a first stitch finger secured at its base to said projection and extending horizontally from said projection in spaced parallel relationship to said side edge, to define a first needle receiving opening between said first finger and said side edge, a second stitch finger secured at its base to said projection and extending horizontally from said projection in spaced parallel relationship to said first finger to define a second needle receiving opening between said first and said second finger, said second finger having a vertical thickness at any longitudinal position thereon being greater than vertical thickness of said first finger at the corresponding longitudinal position.
- 55 5. In an overedge sewing machine having a pair of needles in side-by-side relationship; a throat plate having a side edge thereon and a projection extending laterally from said side edge; a first stitch finger secured at its base to said projection and extending horizontally from said projection in spaced parallel relationship to said side edge, to define a first needle receiving opening between said first finger and said side edge, a second stitch finger secured at its base to said projection and extending horizontally from said projection in spaced parallel relationship to said first finger to define a second needle receiving opening between said first and said second finger, said second finger having a vertical thickness at any longitudinal position thereon being greater than vertical thickness of said first finger at the corresponding longitudinal position.
- 60 6. In an overedge sewing machine having a pair of needles in side-by-side relationship; a throat plate having a side edge thereon and a projection extending laterally from said side edge; a first stitch finger secured at its base to said projection and extending horizontally from said projection in spaced parallel relationship to said side edge, to define a first needle receiving opening between said first finger and said side edge, a second stitch finger secured at its base to said projection and extending horizontally from said projection in spaced parallel relationship to said first finger to define a second needle receiving opening between said first and said second finger, said second finger having a vertical thickness at any longitudinal position thereon being greater than vertical thickness of said first finger at the corresponding longitudinal position.
- 65 7. In an overedge sewing machine having a pair of needles in side-by-side relationship; a throat plate having a side edge thereon and a projection extending laterally from said side edge; a first stitch finger secured at its base to said projection and extending horizontally from said projection in spaced parallel relationship to said side edge, to define a first needle receiving opening between said first finger and said side edge, a second stitch finger secured at its base to said projection and extending horizontally from said projection in spaced parallel relationship to said first finger to define a second needle receiving opening between said first and said second finger, said second finger having a vertical thickness at any longitudinal position thereon being greater than vertical thickness of said first finger at the corresponding longitudinal position.
